UNITED STATES PATENT OFFICE.

HERMAN C. HEATON, OF KENILWORTH, ILLINOIS, ASSIGNOR TO WHEELER CONDENSER & ENGINEERING COMPANY, OF CARTERET, NEW JERSEY.

SURFACE CONDENSER.

Application filed August 11, 1926. Serial No. 128,560.

My present invention relates to a surface condenser and more particularly to that type of surface condenser in which provision is made for the expansion and contraction of the condenser tubes due to the variation in heat to which the apparatus is subjected. The object of my invention is the provision in a surface condenser of an expansion joint placed between the condenser shell and at least one of the tube plates or sheets and preferably connecting the same whereby the ends of the condenser tubes may be shrunk in the tube plates and the tube plate with which the expansion joint member is associated may shift longitudinally of the tubes to provide for the expansion and contraction thereof and wherein the construction is such as to eliminate any leakage between the condensate and the circulating water thereby increasing the efficiency of the apparatus. The construction furthermore is such as to entirely eliminate the use of a double bonnet at the expansion joint end of the condenser as heretofore employed in apparatus of this type.

In the drawing Figure 1 is a longitudinal section illustrating the condenser provided with the improved expansion joint member.

Fig. 2 is an enlarged section illustrating this construction of the joint.

Fig. 3 is a sectional view illustrating another form of the invention, and

Figs. 4, 5 and 6 are also sectional views showing the further forms of the invention.

Referring to the drawing and particularly to Figs. 1 and 2, the condenser shell 10 may be of the usual or any desired form and as is customary is provided at its oppositely disposed ends with flanges 11 and 12. As illustrated, at one end of the condenser there is a tube plate 13 and a bonnet or cover 14. These parts are connected to each other and to the shell at this end thereof by means of bolts 15 passing through the flange 12 of the shell, the outer portion of the tube plate and a flange provided for this purpose in the peripheral portion of the bonnet 14. A plurality of tubes arranged in any nested relationship are indicated at 16 and at this end of the condenser are suitably fixed in the tube plate by means shrunk therein or otherwise.

At the other end of the condenser as illustrated in these figures, there is a movable or shiftable tube plate 17. The opposite

ends of the tube 16 are suitably secured in this tube plate by being shrunk therein or otherwise. This tube plate is connected to a shell by an expansion joint member 18. As illustrated, this expansion joint member 60 is annular and conforms in outline with the end of the shell of the condenser. The inner portion of the expansion joint member is connected to the outer portion of the tube plate by means of a flat ring 19 and suitable stud bolts 20 or otherwise. The outer portion of the expansion joint member extends and lies between the flange 11 at this end of the condenser shell and a flange 21 on a water bonnet or cover 22. These parts are 70 connected to each other and to the shell of the condenser by means of bolts 23 passing through aligned bolt holes provided therefor in the flanges 11 and 21 and the outer portion of the expansion joint member 18. It will 75 be understood that the joints between the expansion joint member and the tube plate are made tight and that a similar condition exists in the joint between the outer portion of the expansion joint member and the shell 80 and bonnet. It will also be understood that suitable provision may be made for the support and shifting movement of the tube plate 17. In this construction it is preferable to provide the end flange of the condenser shell with a shoulder 24 to make provision for an interior recess 25 for the reception of the outer or peripheral portion 85 of the tube plate 17.

In the construction of the condenser as indicated in Fig. 3, the condenser shell internally is provided with a rib or flange connected to which is a bracket 26. Slidably mounted on the bracket 26 are one or more guides 27 which are suitably connected to the tube plate 28 at this end of the shell. The expansion joint member in this structure is indicated at 29. The outer portion of the expansion joint member is connected to the internal flange of the condenser shell by means of a ring 30 and bolts 31, certain of which bolts may also be employed to secure the bracket 26 in place on the internal flange. The inner portion of the expansion joint member 29 is connected to the tube plate 28 by means of a ring 32 and a series of bolts 33, certain of which may also be employed to secure the tube plate 28 to the guide member or members 27. As illustrated in this figure of the drawing, the outer and inner edges 100 105 110

of the expansion joint member may be ribbed as indicated at 34 and 35, making it possible to more readily secure the same in position and to maintain it in place in relationship to the internal rib and the tube plate.

In the construction shown in Fig. 4 the end of the condenser shell 36 is provided with a flange 37. The outer portion of the expansion joint member 38 is placed between the outer surface of this flange 37 and the inner surface of a ring 39. These parts are connected to each other and secured together by means of a series of suitable bolts 40. In this construction the tube plate is indicated at 41. The inner portion of the expansion joint member 38 abuts against the outer portion of this tube plate and the expansion joint member and the tube plate are secured in position between a ring 42 and the flange 43 of a bonnet or cover 44 by means of a series of bolts 45 or otherwise. It will be understood that in this structure the water box includes the bonnet and the tube plate and that these parts are shiftable longitudinally of the tube due to the expansion and contraction thereof, and furthermore that the movable parts at the end of the condenser may be suitably supported.

In the construction shown in Fig. 5, the condenser shell 46 is provided at one end with a boss 47, and a water box 48 with a similar boss 49. In the expansion joint member 50 employed in this construction there is a centrally disposed and outwardly extending rib or loop 51. Then the outer portions of the expansion joint member 50 bears against the faces of the bosses 47 and 49 and respectively are secured in position thereon by means of a ring 52 and a series of bolts 53, and a ring 54 and a corresponding series of bolts 55. In this structure the bonnet 48 is provided with an internal flange 56 against which the outer portion of the tube plate 57 is secured by means of a series of bolts 58 or otherwise. In this structure like that shown in Fig. 4, the bonnet and tube plate are shiftable longitudinally of the tubes due to the expansion and contraction thereof, and may be suitably supported in this movement.

In the construction shown in Fig. 6, the condenser shell 59 at one end thereof is provided with an internal bracket 60 and a guide or guide members 61 are connected to the tube plate 62 by means of rivets as indicated or otherwise. Lying between the face of the bracket 60 and the adjacent surface or surfaces of the guide or guide members 61 there is a roller or ball bearing 63 upon which the guides and tube plate are shiftable due to the expansion and contraction of the tubes. In this structure the expansion joint member is indicated at 64. The outer portion thereof is secured to the condenser shell 65 by means of a ring 66 and a series of bolts

66, while the inner portion thereof is connected to the tube plate 62 by means of a ring 67 and a suitable series of bolts 68.

It will be understood that the several constructions herein shown and described are more or less merely illustrative of the invention, as other and similar constructions may be employed without departing from the spirit thereof. It will furthermore be understood that the expansion joint member may be made of metal or fabric or a combination of the same or other materials which will serve the intended purpose, and that in all instances the connections between the expansion joint member and the parts of the apparatus with which it is associated are made tight irrespective of the form in which the invention may be practiced so as to prevent any leakage between the exhaust steam or condensate and the water or other circulating medium employed in the apparatus.

I claim as my invention:

1. In a surface condenser, a shell, a tube plate, a plurality of tubes each secured at one end in the said tube plate, an expansion joint member, means for connecting the outer portion of the expansion joint member to the shell, means for connecting the inner portion of the expansion joint member to the tube plate whereby the tube plate is movable longitudinally of the tubes due to the expansion and contraction thereof, and means for supporting the said tube plate.

2. In a surface condenser, a shell having a bracket in the inner lower portion at one end thereof, a tube plate, a plurality of tubes each secured at one end in the said tube plate, an expansion joint member, means for securing the said expansion joint member to the said tube plate and shell, and means associated with the tube plate and cooperating with the said bracket on the shell for supporting the said tube plate and acting as a slide upon which the tube plate is shiftable longitudinally of the tubes by the expansion and contraction thereof.

3. In a surface condenser, a shell, a water box at one end thereof, a tube plate, a plurality of tubes each secured at one end thereof in the said tube plate, an expansion joint member, a ring independent of the said shell and water box, the inner portion of the expansion joint member lying between the ring and the adjacent face of the outer portion of the tube plate, means for connecting the inner portion of the expansion joint member in position between the said ring and tube plate, and means for connecting the outer portion of the expansion joint member to the said shell.

4. In a surface condenser, a shell, a tube plate, a plurality of tubes each secured at one end thereof in the said tube plate, an expansion joint member, a ring, devices coacting therewith for connecting the inner portion

of the expansion joint member to the said tube plate, means for connecting the outer portion of the said expansion joint member to the said shell, and means for supporting the said tube plate and upon which the same is shiftable longitudinally of the tubes due to the expansion and contraction thereof.

5. In a surface condenser, a shell, a water box at the end of the shell, a tube plate, a plurality of tubes each secured at one end in the tube plate, an expansion joint member, and means for connecting the expansion joint member to the tube plate and to the shell so that the expansion joint member 10 and the means for securing the same in position lie within the water box.

6. In a surface condenser, a shell, a water box at the end of the shell, a tube plate, a plurality of tubes each secured at one end

20 in the tube plate, an expansion joint member, means for connecting the expansion joint member to the tube plate and to the shell so that the expansion joint member and the means for securing the same in position lie

25 within the water box, and devices for supporting the tube plate and upon which the same is shiftable longitudinally of the tubes due to the expansion and contraction thereof.

7. In a surface condenser, a shell, a water 30 box at one end of the shell, a tube plate, a plurality of tubes each secured at one end thereof in the tube plate, an expansion joint member, a ring, means for connecting the inner portion of the expansion joint member to the peripheral portion of the tube plate so

that the same lies between the ring and the tube plate, and means lying within the water box for connecting the outer portion of the expansion joint member to the said shell.

8. In a surface condenser, a shell, a water 40 box at one end of the shell, a tube plate, a plurality of tubes each secured at one end thereof in the tube plate, an expansion joint member, a ring, means for connecting the inner portion of the expansion joint member 45 to the peripheral portion of the tube plate so that the same lies between the ring and the tube plate, means lying within the water box for connecting the outer portion of the expansion joint member to the said shell, 50 and devices for supporting the tube plate and upon which the same is shiftable longitudinally of the tubes due to the expansion and contraction thereof.

9. In a surface condenser, a shell, a water 55 box, a tube plate, a plurality of tubes each secured at one end in the said tube plate, an expansion joint member, an annular member independent of both the shell and water box, the inner portion of the expansion joint 60 member being between the annular member and an adjacent face of the outer portion of the tube plate, means for connecting the inner portion of the expansion joint member between the said annular member and the tube plate, and means for connecting the outer portion of the expansion joint member to the shell.

Signed by me this 8th day of July, 1926.

HERMAN C. HEATON.
